UNITED STATES PATENT OFFICE.

PETER THOMPSON, OF EL CAMPO, TEXAS.

SHOW-CASE.

No. 908,710.

Specification of Letters Patent.

Patented Jan. 5, 1909.

Application filed April 22, 1908. Serial No. 428,663.

To all whom it may concern:

Be it known that I, PETER THOMPSON, a citizen of the United States, residing at El Campo, in the county of Wharton, State of Texas, have invented certain new and useful Improvements in Show-Cases; and I do hereby declare the following to be a full, clear, and exact description of the invention, such as will enable others skilled in the art 10 to which it appertains to make and use the same.

The present invention relates to improvements in show-cases, and it resides, generally, in the provision of a show-case which 15 includes a sliding bowed door located at the front portion thereof and operated from behind by the dealer, to permit a customer to gain access to the interior of the case for the purpose of making his selection from 20 the goods displayed therewithin.

In dealing in certain classes of goods, cigars, for example, it is ordinarily customary for the dealer to pick up a handful of cigars from the box indicated by the purchaser and place the same upon the top of 25 the case, the purchaser then choosing one or more cigars therefrom; this method, however, is objectionable in that the cigars become of necessity injured to a certain extent 30 on being removed from and replaced in the case, and furthermore on being replaced, are frequently returned to the wrong boxes.

The present invention, therefore, aims primarily to overcome these objections by 35 providing a show-case in which the sliding front door permits access to the interior of the case and thus enables the purchaser to make his selection directly from the stock contained therein.

40 More especially, the invention resides in the specific construction of the supporting members to which the sliding door is attached at its opposite ends; in the particular device employed for opening and closing the 45 door; and in the provision of catches adapted for engagement with said door-operating device, to lock the door both in its open and in its closed position.

The invention still further resides in the 50 provision of a show-case of the above specified type which is exceedingly simple in its construction and is possessed of the requisite strength, durability and efficiency, and may be manufactured at a comparatively low cost.

55 The preferred embodiment of the invention is illustrated in the accompanying

drawings in which corresponding parts or features, as the case may be, are designated by the same reference numerals throughout the several views, wherein:

60 Figure 1 is a front elevation of the improved show-case, with the sliding door partly open. Fig. 2 is a transverse section therethrough, showing the operating lever. Fig. 3 is a perspective view showing the back and one of the ends of the case. Fig. 4 is a longitudinal vertical section. Fig. 5 is a detail view of one of the wheels to which the ends of the door are attached. Fig. 6 is an enlarged fragmental detail view of one 65 of the levers and the catch carried thereby.

Referring more particularly to the drawings, 1 designates the base of the case, 2 and 3 its end walls, 4 its rear wall or back, 6 the front wall, and 7 its top, the case being divided into two sections by a vertical partition 8, which forms the inner wall of both 70 sections and is similar in shape to the walls 2 and 3.

The front of the case includes a plane 80 lower section, and a bowed upper section semi-cylindrical in cross section, the last-mentioned section consisting in turn of a stationary lower member 9 and a sliding upper member or door 10, whose opposite 85 ends fit in concentric semi-cylindrical guide ways 11 formed in the inner faces of the walls 2 and 3, and in both faces of the partition 8, while the lower edge of the door registers with a longitudinal opening 12 90 formed in the front edge of the floor 13 which extends from end to end of the case and occupies a common plane with the centers of the guide ways 11, each section of the case being thus divided into an upper 95 compartment 14 and a lower compartment 15. The door is secured at each end to the rim 16 of a circular spider or wheel 17 rotatably mounted upon a pin 18, which projects laterally from the adjacent end of 100 the floor and passes through an axial opening formed in the hub 19 of the spider, it being understood that the floor is formed in two parts, each of which terminates at its ends short of the corresponding walls 2 or 105 3 and of the partition.

The back of each section of the case is provided with pairs of sliding doors 20 and 21 by means of which access may be had to the upper and lower compartments into 110 which the interior of the case is divided, each upper door having a tongue and groove

connection with the upper and central rails 22 and 23 and each lower door a similar connection with said central rail and with the rear wall of the base.

5 As above stated, each sliding door is supported at its opposite ends upon a pair of annual spiders 17, to whose rims the door is attached, each of the spiders being connected at a point diametrically opposite 10 that at which the door is fastened thereto with a counter-weight 24, this counter-weight being in the nature of a horizontal bar which is disposed longitudinally of the case and is attached at its opposite ends to 15 the corresponding spokes of the spiders, the counter-weight being disposed at all times within the lower compartment of each section of the case.

The sliding movement of each door is 20 effected by means of an operating lever 25 whose front end extends beneath the lower edge of the door and is bent upwardly therearound and is pivoted to a pin 26 secured at opposite ends in a pair of laterally-projecting spaced ears 27 formed upon a 25 plate 28 secured to the front face of the door. The rear end of each lever projects through an opening formed in the central rail 23 of the back and terminates in a 30 handle 29. By reason of this construction, it will be apparent that when the dealer who stands behind the case moves either 35 lever rearwardly, the door to which the front end of the lever is connected will be moved downwardly, thus exposing the interior of the case and permitting the customer to make his selection from the various boxes of cigars contained therein. When such selection has been made, the 40 dealer moves the lever forwardly to its original position, thus closing the door. Each lever is further provided with a pair 45 of openings 31 and 32 in either of which a spring catch 30 is designed for engagement, to retain the lever either in its normal or retracted position, or in its projected position, one of said openings being formed through the lever near its handle 29, while the other opening is located a slight distance 50 in advance of the first mentioned opening.

The case may be made in any desired size and of any preferred material, and of any number of sections, each section having a sliding door which is operated by a separate 55 lever. The top, ends and front of the case are preferably in the form of glass covered frames, the doors having a similar construction, as shown, to permit the contents of both compartments of the case to be visible.

60 The hub 19 of the spider or wheel 17 through which the pin 18 projects may, if preferred, be provided with an interiorly-located series of anti-friction bearings.

Detailed illustration of this structure, however, is omitted, it being merely indicated 65 in Fig. 4.

Each section of the case has located therewithin, a receptacle for containing water to moisten the cigars.

What is claimed is:

1. A show-case, comprising, in combination, a floor provided adjacent its front edge with a longitudinal slot; an upstanding cross frame located at each end of the floor and having an arcuate guide-way 70 formed in its inner face; a bowed door having its ends working in said guide-ways and its lower edge registering with the opening in the floor, said door being capable of movement downwardly through said 75 opening; a rotatably-mounted member located at each end of the floor and having its outer edge attached to the adjacent end of the door; a counter-weight beam connecting said members; an endwise movable lever having its front end secured directly to one edge of the door, and its rear end projecting through an opening formed in the back of the case, for opening and closing 80 the door; and means located exteriorly of the case and arranged for engagement with said lever in its projected and in its retracted position, to retain the door in its open and in its closed position.

2. A show-case, comprising, in combination, a floor provided adjacent its front edge with a longitudinal slot; an upstanding cross frame located at each end of the floor and having an arcuate guide-way 90 formed in its inner face; a bowed door having its ends working in said guide-ways and its lower edge registering with the opening in the floor, said door being capable of movement downwardly through said 95 opening; a rotatably-mounted member located at each end of the floor and having its outer edge attached to the adjacent end of the door; a counter-weight beam connecting said members; an endwise movable lever having its front end secured directly 100 to one edge of the door, and its rear end projecting through an opening formed in the back of the case for opening and closing the door, said projecting end being provided with a pair of openings; and a spring 105 catch secured to the back of the case and arranged for engagement in said openings, to retain the door in open and closed position.

In testimony whereof, I affix my signature, in presence of two witnesses.

PETER THOMPSON.
